United States Patent Office

Des. 183,902
Patented Nov. 11, 1958

183,902

LAWN SPRINKLER

Edwin W. Smith, Climax, Mich., assignor to Atlas Press Company, Kalamazoo, Mich., a corporation of Michigan

Application January 2, 1958, Serial No. 49,098

Term of patent 14 years

(Cl. D91—1)

I claim:

The ornamental design for a lawn sprinkler, as shown.
